UNITED STATES PATENT OFFICE.

LUTHER C. CROWELL, OF BROOKLYN, NEW YORK.

PASTING APPARATUS.

SPECIFICATION forming part of Letters Patent No. 360,860, dated April 12, 1887.

Application filed June 25, 1886. Serial No. 206,195. (No model.)

To all whom it may concern:

Be it known that I, LUTHER C. CROWELL, a citizen of the United States, residing at Brooklyn, county of Kings, and State of New York, 5 have invented certain new and useful Improvements in Pasting Apparatus, fully described and represented in the following specification and the accompanying drawings, forming a part of the same.

This invention relates to an apparatus for applying a line of paste to a web or sheet of paper while the latter is on the run.

The apparatus embodying the invention may be used in connection with many classes of machines which operate upon a web or sheet of paper; but it is especially adapted for use in connection with a sheet associating or folding mechanism. In the case of a sheet-associating mechanism it may be used to apply a 10 line of paste to one sheet of each pair before they are associated, so that when associated the two sheets of the pair will be united. In the case of a sheet-folding mechanism it may be used to apply a line of paste to the sheet or 15 a part of the sheet before it is folded, so that when folded the two parts of the sheet which are brought together by the folding will be united.

As a full understanding of the invention 20 can be best given by a detailed description of a mechanism embodying the same, all further preliminary description will be omitted and a full description of such a mechanism will be given, reference being had to the 25 accompanying drawings, in which—

Figure 1 is a plan view of a pasting mechanism embodying the present invention, showing the same applied to or combined with an ordinary form of sheet-folding mechanism, so 30 much of the folding mechanism being shown as is necessary to illustrate the operation of the pasting apparatus. Fig. 2 is a sectional elevation of the same, taken on the line $x-x$ of Fig. 1. Fig. 3 is a plan view, upon an enlarged 35 scale, of the pasting apparatus alone. Fig. 4 is a sectional elevation of the same, taken on the line $x-x$ of Fig. 3; and Figs. 5 to 13 are sectional views, upon a still larger scale, illustrating the construction and operation of the 40 apparatus, the parts being shown in different 50 positions in the several figures, as will be hereinafter explained.

Referring particularly to Figs. 1 and 2, it is to be understood that the folding mechanism therein partially illustrated is of an ordinary 55 form capacitated to impart two folds to a sheet, said folds being at right angles to each other. This mechanism consists of two pairs of folding-rolls, 90 91, which are arranged at right angles to each other in the usual manner, and 60 two vibrating folding-blades, 92 93, which are operated, in the usual manner, to double the sheets into the bite of the rolls. The folding mechanism is provided with the usual tapes, 20 21, and guides 22 for conveying the sheets 65 into position above the rolls 90, and with the usual tapes, 23, and guides 24 for conveying the folded sheets from the rolls 90 into position above the rolls 91. The folding mechanism is also provided with the usual stops, 25 70. 26, for arresting the sheets in position above the folding-rolls. The sheet A is brought forward above the rolls 90 and guides 22 by the tapes 20 21 in the usual manner until it arrives at the stops 25. The blade 92 is then vibrated 75 quickly downward, so as to double the sheet into the bite of the rolls 90, thus folding it longitudinally upon its central line. From the rolls 90 the folded sheet is carried outward above the rolls 91 by the tapes 23 until it arrives at the 80 stops 26, and, as its folded edge arrives at these stops, the blade 93 is vibrated quickly 85 downward, so as to double the sheet into the bite of these rolls, thus giving it a second fold at right angles to the first fold. When a sheet 90 is folded in this manner, it is frequently desirable—as, for example, when the sheet is printed for an eight-page paper—that the two halves of the sheet, or what, after it is cut along the line of the first fold, becomes the two sheets of the product, should be united along the line 95 between their printed pages, which line, when the sheet is folded a second time, is also usually the line of the second fold. The pasting apparatus forming the subject-matter 100 of the present invention is especially adapted to accomplish this result. The pasting mechanism proper consists, broadly speaking, of a single-acting force-pump, which is arranged to draw in a supply of paste upon its suction-stroke and to discharge the same in a fine stream upon the moving sheet during its reverse stroke, thereby applying a fine line of paste to one-half of the sheet, which, when the

two parts of the sheet are brought together, serves to unite them.

Referring, now, to Figs. 1 to 7, the construction and organization of the pasting apparatus will be described. The pasting apparatus is supported upon a rod or shaft, 94, which extends between the side frames of the machine above the folding-rolls 90. This shaft is provided with arms or brackets 95, which support a paste fountain or vat, 100, in which is arranged a vertical cylinder, 99, the lower end of which extends through the bottom of the vat and forms a nozzle, 9, having a contracted opening, 2. The cylinder 99 is provided with a piston or plunger, 98, having a stem or rod, 27, which extends above the upper end of the cylinder and through an opening in the upper end of a tubular shell, 97, arranged to move up and down upon the cylinder 99. The piston-rod 27 is provided with two adjustable nuts or collars, 8, located some distance apart upon opposite sides of the end of the shell 97, as shown in Fig. 5. The cylinder 99 is provided, just below the point reached by the piston upon its downward stroke, with one or more openings, 6, through which the paste is drawn into the cylinder upon the suction-stroke of the piston, and the shell 97 is provided with a corresponding number of openings, 7, which are so arranged that when the shell is at the limit of its downward stroke they will partly or wholly coincide with the openings 6. The purpose of this will be made clear when the operation of the apparatus is explained. The piston or plunger 98 is provided upon its under side with a slender rod or needle, 13, which is of such length that as the piston nears the limit of its downward stroke it will enter the contracted opening 2 of the nozzle 9. This needle serves not only to cut off the discharge of the paste at the end of the downward stroke of the piston, but also to clear the opening 2 in case it should become clogged by any hard lumps in the paste. The shell 97 is provided upon opposite sides with studs 10, which are engaged by arms 28, mounted loosely upon a rock-shaft, 96, which is supported in bearings in the arms 95. The arms 28 are connected together by a web, 29, which also forms a shoulder or abutment, 3, the purpose of which will be presently explained.

The arms 28 are provided with rearward extensions, 31, which are so arranged that as the arms are rocked upward they will engage with the shaft 94, and thus limit the upward movement of the arms, and the arms 28 are also provided with a spring, 30, the tendency of which is to rock the arms upward and hold them in their raised position, with the extensions 31 in engagement with the shaft 94. The shaft 96 is provided between the arms 28 with a collar, 32, which is rigidly secured to the shaft and is provided with a projection, 19, which carries a pivoted pawl or dog, 33, which is so arranged that as the shaft 96 is rocked it will engage with the shoulder 3 and depress

the arms 28 against the tension of the spring 30, as will be hereinafter more fully explained. The shaft 96 is also provided with a loose sleeve, 34, having a circumferential slot, 4, in which plays a pin, 5, projecting from the shaft 96. By this means it will be observed that the sleeve 34 has a limited movement independent of the shaft, the purpose of which will appear when the operation of the apparatus is explained. The sleeve 34 is provided at its inner end, and beneath the end of the pawl 33, with a cam-like projection, 12, which is so arranged that when the pin 5 is in one end of the slot 4 it (the projection 12) will raise and hold the pawl 33 out of engagement with the shoulder 3, while when the pin is in the other end of the slot it (the projection 12) will be removed from beneath the pawl and allow it to fall and engage with the shoulder 3. The sleeve 34 is provided at its outer end with an arm or feeler, 35, which projects downward and forward, and is so arranged that when in its raised position it will lie just above the path of the sheet A as it is carried into position above the folding-rolls 90.

The operation of the pasting apparatus thus constructed and organized is as follows: In describing this operation it will be assumed that the rock-shaft 96 is provided with any suitable form of connections, (not shown,) by which it is rocked at the proper time and to the proper extent to produce the movements of the several parts, which will now be described. The connections for rocking the shaft 96 will be so timed that, as the sheet A is carried forward above the folding-rolls 90, the shaft 96 will be in the position shown in Figs. 1 to 6—that is to say, at the limit of its movement from left to right. It will be observed that when the shaft 96 is in this position the feeler 35 is raised above the path of the sheet A, and also that the arms 28, and with them the shell 97 and piston 98, are at the limit of their upward movement, in which position they are arrested by the extensions 31, which are in contact with the shaft 94. It will also be observed that when the parts are in this position the projection 12 is under the pawl 33, so as to hold the pawl in its raised position. As the leading end of the sheet A passes forward above the folding-rolls 90, the shaft 96 will commence to rock from right to left, as indicated by the arrow in Fig. 5. As the shaft is thus rocked the weight of the feeler 35 will cause the sleeve 34 to move with the shaft, so that the pin 5 will remain against the end of the slot 4, as shown in Fig. 6, and thus cause the projection 12 to hold the pawl 33 raised until the feeler 35 has been lowered so that its end rests upon the sheet A, as shown in Fig. 7. As soon as the feeler 35 comes into contact with the sheet it will be arrested thereby, and thus the sleeve 34 and projection 12 will be arrested, so that the continued movement of the shaft 96 will carry the pawl 33 forward off the projection 12 and allow it to fall in front of the shoulder 3, as shown in Fig. 8.

The pin 5 will then move idly back in the slot 4, as also shown in said figure. As soon as this takes place the pawl 33 will engage with the shoulder 3, so that the continued movement of the shaft 96 will rock the arms 28 downward against the tension of the spring 30 and raise the extensions 31 away from the shaft 94. As the arms 28 are thus rocked downward they will move the shell 97 downward over the cylinder 99 until the upper end of the shell comes into contact with the lower nut, 8, on the piston-rod 27, and by the time this takes place the lower end of the shell will have covered the openings 6, as shown in Fig. 8, thereby 15 confining in the cylinder 99 the paste which was drawn into the cylinder upon the last up-stroke of the piston 98. The parts will arrive in this position just before the folding-blade 92 descends to fold the sheet into the bite of the 20 rolls 90. As the blade 92 descends and folds the sheet into the bite of the rolls 90; and while the sheet is being carried between the rolls, the continued movement of the shaft 96 and arms 28 will move the sleeve 97, and with it the piston 98, downward to the position shown in Fig. 9, and so on to the position shown in Fig. 10, and when the parts are in this position the shaft 96 will be at the limit of its movement from right to left. As the piston 98 is forced 25 downward from the position shown in Fig. 8 to the position shown in Fig. 10 it will force a small stream or thread of paste out through the contracted opening 2, and this small stream of paste, falling upon the sheet, which at this 30 time is moving inward beneath the nozzle 9, will form a fine line of paste along the central line of the half *a* of the sheet A, so that as the two halves of the sheet are brought together in passing between the rolls 90 they will be 35 united. The connections by which the shaft 96 is rocked will be so timed that the parts will arrive in the position shown in Fig. 10 as or just after the edge of the sheet has been drawn inward past the nozzle 9. It will be observed, 40 by reference to Fig. 10, that as the shell 97 and piston 98 reach the limit of their downward movement the needle 13 enters the opening 2, thereby nearly or quite closing said opening, so as to cut off the discharge of paste, and at 45 the same time the openings 6 7 are brought into register, so as to allow the paste to be expelled from the cylinder through these openings for the remainder of the downward movement of the piston. After the parts have arrived in the position shown in Fig. 10, the movement of the shaft 96 will be reversed, as indicated in Figs. 11 and 12, and rocked back to the position shown in Fig. 5. As the shaft 96 is thus moved back to its original position the 50 feeler 35 will remain in its lowered position until the pin 5 engages with the lower end of the slot 4, during which time the pawl 33 will be carried up onto the projection 12, as shown in Fig. 12. After the pawl 33 has been thus raised the pin 55 will cause the sleeve 34 to move with the shaft 96 during the remainder of its return movement, so as to raise the feeler 35 back to

the position shown in Figs. 5 and 6 in time to permit the next sheet to pass beneath it. As the shaft 96 makes its return movement, as 70 just stated, the spring 30 will raise the arms 28, and, as the arms 28 are raised, they will first raise the shell 97 from the position shown in Fig. 10 until its upper end comes into contact with the nut 8 upon the upper end of the 75 piston-rod 27, after which the continued upward movement of the arms 28 will raise the shell still farther, so as to uncover the openings 6, and at the same time raise the piston 98, and thereby cause the piston to draw in a 80 supply of paste through the openings 6, and this will continue until the extensions 31 come into contact with the shaft 94 and arrest the arms 28, as shown in Figs. 5 and 6. In this operation it is of course to be understood that 85 the paste-vat is filled with paste to a height above the openings 6.

In an apparatus of this character it is of course highly important that means should be provided by which the pasting mechanism 90 proper will be prevented from operating except when a sheet is present beneath it to receive the paste, as otherwise paste might be ejected from the cylinder 99 when no sheet was present to receive it, and the paste would 95 in such case fall upon and smear the folding-rolls and other parts of the machine. This is obviated by the arm or feeler 35 and projection 12. To make this clear, let it be supposed that when the shaft 96 is rocked from 100 right to left, as already described, no sheet is in position beneath the feeler 35. In such case the feeler 35, instead of being arrested in the position shown in Fig. 7, will continue to move downward and the sleeve 34 will continue to 105 move with the shaft 96 during the whole of its movement from right to left, as shown in Fig. 13. This being the case, the projection 12 will remain beneath the pawl 33, so that the pawl will be held in its raised position and 110 prevented from engaging with the shoulder 3, and as a consequence the arms 28 and the shell 97 and piston 98 will not be operated and no paste will be ejected from the cylinder 99.

By reference to Figs. 1 to 4 it will be observed that the ends of the arms 28 are forked, so as to permit the studs 10 to be readily disconnected from the arms, and also that the paste-vat 100 is so connected to the arms or brackets 95 that it can be shifted in position. By this 110 means it is made possible to readily remove the shell 97 and piston 98 from the cylinder 99, so that the parts can be cleaned, as often as may be necessary, with very little trouble and delay.

The folding mechanism herein shown forms no part of the present invention, but is shown merely for the purpose of illustrating one of the many ways in which the pasting apparatus which embodies the invention can be usefully 130 applied. The pasting apparatus can be used equally well in connection with other forms of folding mechanism—such, for example, as those in which the first fold is made trans-

versely instead of longitudinally of the sheet, or those which impart only a single fold instead of two or more folds, or those in which the fold or folds is or are made by a rotating blade and rolls, or a tucking-blade and nipping-jaws.

The pasting apparatus embodying the present invention may also be used equally well in connection with any of the ordinary forms of sheet-associating mechanism to apply a line of paste to certain of the sheets, so that when they are associated they will be united along the paste-line. It is also to be remarked that in some cases it may be found desirable to so arrange or locate the pasting apparatus that the lines of paste will be applied to the web before it is severed into sheets, the lines of paste being in such case applied in such positions that when the web is severed into sheets and the sheets associated or folded the sheets or the parts of the sheet will be united at the proper point or points.

The pasting apparatus herein shown embodies the invention in what I regard as its most complete and desirable form. Changes may, however, be made in certain parts and certain parts may be omitted without wholly departing from the invention. In some cases it may not be found necessary to provide the apparatus with means for preventing the discharge of the paste from the cylinder 99 when it happens that a sheet is not present beneath the cylinder to receive the paste. This would be the case when, owing to the organization of the machine, it happened that the paste falling from the nozzle 9 would not lodge upon any part of the machine where it would do harm. In such case the sleeve 34 and its projection 12 and feeler 35 may be omitted, or these parts, and also the pawl 33, extensions 31, and spring 30, may be omitted, the arms 28 being connected rigidly to the shaft 96. When the arms 28 are connected rigidly to the shaft 96, the shaft will of course have a less movement than in the case shown. It is also to be understood that the apparatus, instead of being supported in the manner shown, may be supported in any other convenient or suitable manner, and also that, instead of two, there may be only one of the arms 28. It is also to be remarked that, although the shell 97 forms the best form of valve which I have devised for controlling the openings 6, through which the paste is drawn into the cylinder 99, other forms of valve apparatus may be employed for this purpose without departing, essentially, from the invention. In some cases the piston or plunger 98 and the shell 97, or other valve apparatus for controlling the admission of the paste to the cylinder 99, may be operated independently of each other.

In using some kinds of paste the needle 13 may not be necessary, and it may therefore in such case be omitted.

65 What I claim is—

1. An apparatus for applying a line of paste to a moving sheet or web, consisting of the

cylinder 99, having the contracted discharge-opening 2, and an opening or openings, 6, for the admission of paste, the reciprocating piston or plunger 98, and the shell 97, for covering the opening or openings 6, substantially as described.

2. In an apparatus for applying a line of paste to a moving sheet or web, the combination, with the cylinder 99, having the contracted discharge-opening 2 and an admission opening or openings, 6, of the piston or plunger 98 and the reciprocating shell 97, substantially as described.

3. In a pasting apparatus, the combination, with the cylinder 99, having the contracted discharge-opening 2, of the reciprocating piston or plunger 98, having the needle 13, which is arranged to enter said discharge-opening as the piston reaches the end of its stroke, substantially as described.

4. In a pasting apparatus, the combination, with the cylinder 99, having the contracted discharge-opening 2 and an admission opening or openings, 6, of the shell 97, for closing the opening or openings 6, and the piston or plunger 98, having the rod 27 and nuts 8, whereby the piston or plunger 98 is operated by the movement of the shell, substantially as described.

5. In a pasting apparatus, the combination, with the cylinder 99, having the contracted discharge-opening 2 and an admission opening or openings, 6, of the piston or plunger 98, having the needle 13, arranged to enter the discharge-opening as the piston or plunger arrives at the end of its stroke, and the shell 97, arranged to close the admission opening or openings and provided with an opening or openings, 7, arranged to communicate with the admission opening or openings as the piston or plunger arrives at the end of its stroke, substantially as described.

6. The combination, with the cylinder 99, having the contracted discharge-opening 2 and an opening or openings, 6, through which the paste is admitted, of the piston or plunger 98 and a valve for closing the admission opening or openings before it or they is or are covered by the piston or plunger, all substantially as described.

7. The combination, with means for advancing a sheet or web, of an apparatus for applying a line of paste thereto, consisting of the cylinder 99, having the contracted discharge-opening 2 and the reciprocating piston or plunger 98, all substantially as described.

8. The combination, with means for advancing a sheet or web, of the paste-vat 100, the cylinder 99, provided with the piston or plunger 98 and having the contracted discharge-opening 2, and connections for reciprocating said piston or plunger, all substantially as described.

9. The combination, with means for advancing a web or sheet, of the cylinder 99, having the contracted discharge-opening 2 and provided with the piston or plunger 98, the feeler

35, arranged to be arrested by the web or sheet, and connections between the feeler and said plunger, whereby the latter is put into operation by the arrest of the former, all substantially as described.

10. The combination, with means for advancing a web or sheet, of the cylinder 99, piston or plunger 98, rock-shaft 96, feeler 35, pawl 33, and connections, all substantially as described.

In testimony whereof I have hereunto set my hand in the presence of two subscribing witnesses.

LUTHER C. CROWELL.
